[57] **CLAIM**

The ornamental design for a backgammon board, as shown and described.

DESCRIPTION

FIG. 1 is a perspective view of a backgammon board, showing my new design;

FIG. 2 is a front elevational view thereof, the rear being identical;

FIG. 3 is a left side elevational view thereof, the right side being identical;

FIG. 4 is a top plan view of the backgammon board shown in FIG. 1; and,

FIG. 5 is a bottom plan view of the backgammon board shown in FIG. 1.
